DESIGN FOR A WALL BRACKET LAMP

Otto G. Hildebrand, Cleveland, Ohio

Application November 14, 1935, Serial No. 59,569

Term of patent 14 years

To all whom it may concern:

Be it known that I, Otto G. Hildebrand, a citizen of the United States, residing at Cleveland, in the county of Cuyahoga and State of Ohio, have invented a new, original, and ornamental Design for a Wall Bracket Lamp, of which the following is a specification, reference being had to the accompanying drawing, forming part thereof, wherein Fig. 1 is a side elevation and Fig. 2 is a front elevation of the wall bracket lamp showing my new design.

I claim:—

The ornamental design for a wall bracket lamp, substantially as shown and described.

OTTO G. HILDEBRAND.
